UNITED STATES PATENT OFFICE

2,529,135

ELECTRIC INDUCTION APPARATUS

Guglielmo Camilli, Pittsfield, Mass., assignor to
General Electric Company, a corporation of
New York

Application December 22, 1948, Serial No. 66,806

2 Claims. (Cl. 175—358)

1

This invention relates to electric induction apparatus and more particularly to improvements in porcelain-clad liquid filled instrument transformers.

By the term "porcelain" I wish to include all brittle ceramic and vitreous dielectric materials. In order to reduce the overall height of high voltage instrument transformers at least a part of the transformer proper, that is to say, the core and coil assembly, often is mounted within a cylindrical porcelain insulator which constitutes the main dielectric material between the high voltage line terminals of the transformer and the portions of the transformer which are normally at ground potential. It is customary in many instances substantially to fill the porcelain enclosure with a dielectric liquid which impregnates and fills the voids in the solid insulation between the different potential electrodes or other parts in the device. When a conventional porcelain-clad liquid filled transformer fails internally, the resultant electric arc decomposes the liquid and solid insulation and there is a rapid increase in the amount of gas which is a product of such decomposition. This causes the production of very high pressures, and, in fact, pressure waves have been observed having a peak value in excess of one-thousand pounds per square inch and the maximum value of these pressure waves is often reached in $1/1000$ of a second or less. This very steep front of the pressure wave almost invariably cracks the porcelain and what is worse the energy in the expanding gas accelerates the porcelain fragments to a high velocity with resulting extreme danger to nearby personnel and severe damage to adjacent equipment.

In accordance with the invention, there is provided an electric induction device of this type which, while perhaps not strictly explosion-proof, may aptly be described as explosion-safe in that the pressure wave which reaches the porcelain is greatly attenuated, thus very much reducing the likelihood of the porcelain being cracked and relatively slow acting means is provided for relieving the pressure so that even though the porcelain should crack, there will be very little pressure energy available for accelerating the porcelain fragments. These results are obtained by means of a special liner for the porcelain insulator in combination with means for relieving the pressure within the casing.

An object of the invention is to provide a new and improved electric induction apparatus.

Another object of the invention is to provide

2

an explosion-safe porcelain-clad liquid filled instrument transformer.

The invention will be better understood from the following description taken in connection with the accompanying drawing and its scope will be pointed out in the appended claims.

In the drawing Fig. 1 is a vertical sectional view through a high voltage current transformer embodying the invention, Fig. 2 is a similar view of a modification, Fig. 3 is an oscillogram of a pressure wave inside the special liner caused by an explosion in the transformer, Fig. 4 is an oscillogram showing how the pressure wave of Fig. 3 has been attenuated by the special liner.

Referring now to the drawing and more particularly to Fig. 1, there is shown therein a high voltage current transformer comprising a cylindrical porcelain insulator 1 inside of which is mounted a core and coil assembly indicated generally at 2. The lower end of the porcelain cylinder 1 is provided with a metal mounting flange 3 which is attached thereto by any suitable bonding means 4. For closing the lower end of the cylinder 1 a metal plate 5 is attached to the mounting flange or ring 3 by bolts 6, and the entire device is mounted on any suitable support such as the hollow cylindrical member 7.

The core and coil assembly 2 comprises a solid insulated high voltage winding 8 of relatively few turns which links a solid insulated low voltage winding 9 which is wound on a circular magnetic core (not shown). The leads for the high voltage winding 8 are contained in a sleeve 10 extending upwardly from the winding 8 and they emerge from the upper end of the sleeve 10 as conductors 12 which are attached to the inner ends of bushings 13 which are mounted in the walls of a closure member 14 for the top of the device. The bottom of the closure 14 is sealed to a metal ring 15 which in turn is attached by bolts 16 to a top mounting flange 17 which is attached to the porcelain bushing 1 in the same manner that the bottom flange 3 is attached thereto. The entire device is filled to the level indicated by any suitable dielectric liquid such as mineral oil or askerol.

For protecting the porcelain 1 from the effects of steep front high pressure waves in the liquid produced by an internal fault in the transformer, 50 a special cylindrical liner 18 is interposed between the porcelain 1 and the core and coil assembly 2. This cylindrical liner consists of an inner resilient relatively mechanically weak cylinder 19 inside a rigid mechanically strong outer cylinder 20. One such liner which has given good

results has a wall one inch thick consisting of an inner cylinder three-fourths of an inch thick of soft relatively loosely wound paper which has not been impregnated with any hardened binder and an outer cylinder one-fourth of an inch thick of glass cloth which has been impregnated with a suitable hardened synthetic resin or a polymerized solventless varnish.

The walls of this liner or duplex cylinder act like a low-pass filter and decrease the steepness of the shock wave which reaches the porcelain wall. This action is shown by a comparison of Figs. 3 and 4, Fig. 3 being a pressure wave inside the liner 18 having a maximum value of 3,720 pounds per square inch. Fig. 4 shows what is left of the pressure wave of Fig. 3 after it gets through the liner 18. That is to say, Fig. 4 illustrates the pressure wave which actually reaches the porcelain 1 as a result of the initial pressure wave of Fig. 3 inside the transformer. The timing dashes at the bottom of Figs. 3 and 4 represent intervals of $1/1000$ of a second.

The space between the cylinder 1 and the liner 18 is effectively sealed at both ends so that none of the gas developed by an arcing fault can get to the inside wall of the porcelain. This is accomplished by having the bottom of the liner 18 rest on the plate 5. This plate is provided with an annular flange 21 to which the liner 18 is attached by bolts 22. The upper seal is obtained by means of a gasket 23 which is clamped in place by means of a ring 24 attached by bolts to the larger ring 15. A further advantage of this construction is that the seal is maintained even though there is differential thermal expansion and contraction of the porcelain 1 and the liner 18. The seals are not liquid tight and the space between the porcelain 1 and the liner 18 is normally filled with liquid. The function of the seals is to prevent high pressure gas in any quantity from entering the annular space between the porcelain 1 and the liner 18 at least during the initial stage of a fault in the transformer.

For relieving the pressure which is built up in the transformer as a result of an internal fault, pressure relief devices are mounted at both the top and the bottom of the transformer. Thus the top of the closure 14 comprises a frangible diaphragm 25 which is clamped between two rings 26 by screws 27. Transverse bars 28 and 29 above and below the diaphragm serve to retain rings 30 having sharp edges which bear against the diaphragm 25. These serve to cut the diaphragm in a number of places when there is a substantial pressure difference between the inside and the outside of the transformer. At the bottom of the transformer there is a central hole in the plate 5 which is closed by a frangible diaphragm 31 which is attached to the plate 5 by a ring 32 and screws 33. This diaphragm is notched or weakened at 34 so that it will readily break when there is a substantial pressure difference between the inside and the outside of the transformer.

The primary winding structure 8 and the combined secondary winding and core structure 9 are mounted in a suitable frame 35 which securely holds those parts in their proper relative position. This frame is securely attached to the member 5 in any suitable manner such as by bolts.

The secondary winding has leads 36 which terminate in secondary winding terminals 37.

The operation of Fig. 1 in minimizing the ef-

fect of an internal explosion has to a large extent already been described incidentally in the above description of the device itself, but the following more detailed description of the operation is thought to be desirable. As the amount of gas given out from an electric arc in the liquid increases rapidly, the yielding of the resilient inner cylinder 19 under the influence of the corresponding increasing pressure effectively reduces the rate of rise of this pressure. At the same time the relatively strong and rigid outer cylinder 18 prevents or greatly reduces the transmission of pressure to the porcelain 1. Consequently even though the porcelain should be cracked by the initial shock wave, practically no sustained high pressure will initially be applied to the porcelain so that none of the broken particles of porcelain can be accelerated outward for any appreciable distance or with any real force. Furthermore, the action of the liner 18 in delaying the application of pressure to the porcelain 1 gives time for the pressure relief diaphragms 25 and 31 to rupture and, of course, as soon as these diaphragms do rupture the pressure inside the liner 18 very rapidly falls to substantially atmospheric pressure. The reason for having both an upper and a lower diaphragm is that electrical failures can occur anywhere inside the transformer and in order to relieve this pressure as quickly as possible it is desirable that the pressure relief diaphragm be as close as possible to the location of the fault. In actual practice the diaphragm which is nearest the fault will rupture first but the other one will almost invariably rupture also so that the transformer will be open at both ends and the pressure will be discharged very rapidly from both ends.

While best results have been obtained with the duplex liner consisting of an inner resilient cylinder and an outer strong rigid cylinder, it will be apparent that either one of these cylinders alone or in combination with the pressure relief diaphragms would also make the transformer much safer than a conventional porcelain clad liquid filled transformer, and, therefore, the invention in its broader aspect is not limited to the two different character cylinders.

In Fig. 2 the transformer is of the so-called eye-bolt type because of the resemblance of its primary winding structure 38 to an eye-bolt. This structure has an elongated neck 39 which is inside a porcelain cylinder 40. Between the neck 39 and the porcelain cylinder 40 is a protective liner 41 which is similar to the liner 18 of Fig. 1 in that it comprises an outer strong and rigid cylinder 42 and an inner resilient cylinder 43. The liner is sealed at its ends to the ends of the porcelain 40 in any suitable manner.

The combined secondary winding and core of the transformer is indicated at 44. The secondary leads 45 are brought out to terminals 46 in the lower part of a housing 47 which is provided with oppositely disposed pressure relief diaphragms 48. The primary and secondary windings of the transformer, as in Fig. 1, are, of course, provided with suitable solid insulation which is adequate to withstand maximum voltage stresses between the parts, but in order to further increase the dielectric strength of the device it is substantially entirely filled with liquid up to a level 49 in a top enclosure 50 which is attached to the top of the porcelain bushing 50 in any suitable manner. A top pressure relief device 51 closes the top of the member 50.

The primary winding has leads 52 which terminate in high voltage terminals 53.

In practice there is practically no potential difference between the high voltage terminals because the primary winding ordinarily has only a very few turns so that the top metal enclosure 14 of Fig. 1 and 50 of Fig. 2 is ordinarily at line potential, whereas the metal members or closures at the opposite end of the porcelain bushings are normally at ground potential.

The operation of Fig. 2 is the same as the operation of Fig. 1.

While there have been shown and described particular embodiments of this invention, it will be obvious to those skilled in the art that various changes and modifications can be made therein without departing from the invention and, therefore, it is aimed in the appended claims to cover all such changes and modifications as fall within the true spirit and scope of the invention.

What I claim as new and desire to secure by Letters Patent of the United States is:

1. An explosion safe porcelain clad liquid filled high voltage transformer, comprising in combination, a normally vertical hollow cylindrical porcelain insulator, a metal closure for the bottom of said cylinder which is normally at substantially ground potential, low voltage terminals mounted on said closure, a metal closure for the top of said cylinder which is normally at line potential, high voltage line terminals mounted on said top closure, a transformer core and coil assembly having high and low voltage windings, said core and coil assembly being between said top and bottom closures and at least partially surrounded by said insulating cylinder, the high voltage winding being connected to the high voltage terminals and the low voltage winding being connected to the low voltage terminals, a protective liner for the porcelain cylinder comprising a duplex cylinder having a relatively thick inner zone of relatively soft insulating material and a relatively thin outer zone of hard insulating material, said liner being sealed to the top and bottom of said porcelain cylinder, pressure relief diaphragms in said top and bottom clos-

ures, and a liquid insulator filling all free space in said device up to a level in said top closure.

2. An explosion safe porcelain clad liquid filled high voltage transformer, comprising in combination, a normally vertical hollow cylindrical porcelain insulator, a metal closure for the bottom of said cylinder which is normally at substantially ground potential, low voltage terminals mounted on said closure, a metal closure for the top of said cylinder which is normally at line potential, high voltage line terminals mounted on said top closure, a transformer core and coil assembly having high and low voltage windings, said core and coil assembly being between the opposite ends of said top and bottom closures and at least partially surrounded by said insulating cylinder, the high voltage winding being connected to the high voltage terminals and the low voltage winding being connected to the low voltage terminals, a protective liner for the porcelain cylinder comprising an inner relatively soft paper loosely packed multi-layer cylinder with walls about one inch thick inside a hard resin impregnated glass cloth multi-layer outer cylinder with walls about one-quarter of an inch thick, said liner being sealed to the top and bottom of said porcelain cylinder, pressure relief diaphragms in said top and bottom closures, and a liquid insulator filling all free space in said device up to a level in said top closure.
